UNITED STATES PATENT OFFICE.

ARCHIE D. COALSON, OF BIRMINGHAM, ALABAMA.

RERAILING DEVICE.

1,243,920.

Specification of Letters Patent. Patented Oct. 23, 1917.

Application filed March 2, 1917. Serial No. 152,022.

To all whom it may concern:

Be it known that I, ARCHIE D. COALSON, a citizen of the United States, residing at Birmingham, in the county of Jefferson and State of Alabama, have invented a new and useful Rerailing Device, of which the following is a specification.

The present invention appertains to rerailing devices and aims to provide a novel, simple and inexpensive construction designed to replace the wheels of a car which has been derailed.

It is the object of the invention to provide a rerailing device having novel and improved features of construction, to enhance the utility and efficiency thereof.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed without departing from the spirit of the invention.

The invention is illustrated in the accompanying drawing, wherein:—

Figure 1 is a plan view of the device as applied to a rail.

Fig. 2 is a bottom view of the device.

Fig. 3 is a longitudinal section taken on the line 3—3 of Fig. 1.

Fig. 4 is a cross section taken on the line 4—4 of Fig. 1.

The present device is constructed of one piece of suitable metal, and can be cast, forged or otherwise manufactured. The device embodies an elongated longitudinal shoe 1 adapted to seat in a horizontal plane upon the tread of the rail, and provided at its outer edge with a depending flange 2 coextensive in length therewith and adapted to overlap the outer side of the tread or head of the rail, as seen in Fig. 4. The shoe 1 is provided at its inner edge with a flat hanger 3 coextensive in length therewith and adapted to overlap the inner side of the tread of the rail. Extending inwardly from the hanger 3 intermediate the ends of the shoe 1 and in a plane slightly below and parallel with the shoe 1 is a horizontal platform 4. Reversed inclines 5 have their upper ends united with the opposite ends of the platform 4, and have their outer edges united with the lower edge of the hanger 3 as does

also the platform 4. The hanger or hanger wall 3 serves to suspend the outer edge portions of the platform 4 and inclines 5 from the tread of the rail upon which the shoe 1 is seated. The shoe extends substantially throughout the length of the device, whereby the device is held firmly in place against the rail. United with the inner edge portions of the platform 4 and inclines 5 is a supporting wall 6, the two halves of which are arranged at an obtuse angle relative to one another so as to converge toward the platform 4 and shoe 1, with the ends of the wall 6 spaced farther from the shoe 1 and rail and the intermediate angle portion thereof. The lower edge of the supporting wall 6 is provided with an inwardly extending flange 7 disposed in a horizontal plane below the plane of the platform 4, and said flange is adapted to seat upon the ties of the track at the inner side of the rail to which the device is applied. The flange 7 has openings 8 whereby the flange can be spiked upon the ties, if desired.

Upstanding from the upper edge of the supporting wall 6 is a guiding flange 9 of the same shape as the supporting wall, as will be apparent in Fig. 1, and this guide flange is preferably of equal height throughout the intermediate portion of said flange at the inner side of the platform 4 extending slightly above the horizontal plane of the shoe 1, as seen in Fig. 4. The device has a reinforcing web or brace 10 between the intermediate portions of the supporting wall 6 and platform 4.

The inclines 5 are provided thereon with longitudinal upstanding ribs 11 which are of triangular or tapered form with their smaller or pointed ends terminating immediately adjacent to the opposite ends of the platform 4 or the adjacent ends of the inclines 5. The ribs 11 extend to the remote ends of the inclines 5, and the remote wider ends of the ribs 11 are of little if any height above the remote ends of the inclines 5, but said ribs 11 increase in height from their remote to their adjacent ends. The adjacent end portions of the ribs have their upper edges or portions horizontal, as at 12, for a short distance, and in the plane of the shoe 1. Those sides of the ribs 11 adjacent to the shoe are arranged at acute angles relative thereto and in the same vertical planes as the opposite halves of the flange 9, while the sides of the ribs 11 adjacent to

the flange 9 are parallel with the adjacent halves of the flanges, to provide converging grooves 13 between them, the inclines 5 providing the bottom of the grooves, and the 5 grooves terminating at the ends of the platform 4.

The remote ends of the inclines 5 and ribs 11 are provided underneath them with bosses 14 disposed transversely and flush 10 with the flange 7 to rest upon the ties, whereby to effectively support the remote ends of the inclines. The bosses 14 have their outer ends spaced from the plane of the hanger wall 3 so as to lie at the inside 15 of the base flange of the rail, as seen in Fig. 4.

In use, the device is adapted to guide a wheel in either direction onto the rail, the wheel moving onto the device at either end. 20 The tread of the wheel travels upwardly upon the respective rib 11 while the flange of the wheel moves within the groove 13 onto the platform 4, upon which the wheel flange can rest and travel horizontally 25 across the platform toward the shoe 1. The wheel flange is directed at an oblique angle from the respective half of the flange 9 across the end of the opposite groove 13 to the outer side of the other rib 11, thereby 30 shifting the wheel outwardly onto the shoe 1, from which the wheel will roll onto the tread of the rail from one end of the shoe. The platform 4 reduces the liability of the 35 wheel rolling back on the incline. The flange 9 serves to shift the wheel outwardly as it is moved up either incline, and from said flange, the wheel is moved to the other side of the corresponding rib 11 which completes the shifting of the wheel onto the 40 shoe 1 and rail.

Having thus described the invention what is claimed as new is:—

1. A rerailing device embodying an elongated shoe to rest upon a rail and having a 45 depending hanger wall at its inner edge, an

inwardly extending platform connected to said wall disposed in a plane below the plane of said shoe, inclines having their upper ends connected to the opposite ends of said platform and having their outer edges 50 connected with said hanger wall, a supporting wall connected with the inner edges of said platform and inclines and having a lower horizontal flange to rest upon the ties, and upstanding longitudinal ribs upon the 55 inclines tapering and increasing in height from their remote to their adjacent ends, and an upstanding guide flange above said supporting wall.

2. A rerailing device embodying an elongated shoe to rest upon a rail and having a depending hanger wall at its inner edge, an inwardly extending platform connected to said wall and disposed in a plane below the plane of said shoe, inclines having their 60 upper ends connected to the opposite ends of said platform and having their outer edges connected with said hanger wall, a supporting wall connected with the inner edges of said platform and inclines and 65 having a lower horizontal flange to rest upon the ties, and upstanding longitudinal ribs upon the inclines tapering and increasing in height from their remote to their adjacent ends, and an upstanding guide flange above said supporting wall, said supporting wall and flange having their halves 70 arranged at an obtuse angle with their ends spaced farther from the shoe than their intermediate portions, and the adjacent 75 ends of said ribs terminating at the adjacent ends of the inclines.

In testimony that I claim the foregoing as my own, I have hereto affixed my signature in the presence of two witnesses:

ARCHIE D. COALSON.
